UNITED STATES PATENT OFFICE.

SPENCER OTIS, OF BARRINGTON, ILLINOIS.

POST CRANE.

Application filed October 2, 1922. Serial No. 591,822.

To all whom it may concern:

Be it known that I, SPENCER OTIS, a citizen of the United States, residing at Barrington, in the county of Cook and State of Illinois, have invented certain new and useful Improvements in Post Cranes, of which the following is a specification.

This invention relates to jib cranes adapted to be mounted with horizontal swinging movement upon stationary pillars or studs in existing structures or upon specially provided stationary posts.

One object of the invention is to provide an improved construction of jib crane in which the sustaining structure and mountings are located at or below the jib level in order that the jib can be positioned high on the supporting post with consequent increase in its vertical range of action and clearance of obstructions. Accordingly, one feature consists in locating a diagonal compression stay beneath a substantially horizontal jib, and connecting together the inner end of the jib and the lower end of this stay through means of a substantially vertical tension member in a manner to form a rigid triangular truss of such integrity as will permit it to be sustained vertically, through the lower end of its stay upon an annular step provided upon the stationary post, and horizontally sustained through its jib, which constitutes the upper horizontal leg of the triangular truss, by means of a strap revolvably embracing the post on a level with the jib.

A further object is to provide means for leveling the jib in the structure above described to better adapt it to serve as a trolley track. Accordingly, another feature consists in extending the ends of the strap parallel with the jib and anchoring them to the crane through the medium of draw bolts, and securing the outer ends of these draw bolts by nuts so that by changing the length of the draw bolts the angle of the crane and consequently the level of the jib, can be determined at will.

A further object is to provide a cheap and readily available construction of shouldered post upon which to mount a jib crane of the kind referred to, and also a cheap and durable construction of roller foot through which the crane bears and travels upon the shoulder. Accordingly, another feature of

the invention consists in building up the stationary post for a trussed jib crane, out of an inner core or body-timber surrounded by a group of reinforcing timbers, which latter terminate in position to form an offset or shoulder to receive the lower end of the crane, and have their ends turned or dressed to form an annular step therefor.

In the accompanying drawings, in which two embodiments of the invention are shown by way of illustration—

Figures 1 and 2 are, respectively, a side elevation and a top plan view of an embodiment in which the foot of the crane is equipped with special shoes bearing frusto-conical rollers which traverse an annular step provided by a specially constructed collar upon the stationary post; and Figure 3 is a section on the line 3^x—3^x of Figure 1.

Figure 4 is a view similar to Figure 1 showing a modified construction of stationary post and of the bearing shoe through which the crane rests thereon.

Figure 5 is a section on the line 5^x—5^x of Figure 4; and

Figure 6 is a section on the line 6^x—6^x of Figure 4.

Referring to Figures 1, 2, and 3, 1 represents a stationary post forming part of a building structure, or provided specially therein, having its lower end fixed in masonry at 2 and its upper end united through flange coupling 3 with a girder, beam, or other available member 4. Located upon the post 1 is a collar 5 constructed with an annular beveled step 6 sustained by webs 7.

8 represents a crane jib sustained vertically by a pair of diagonal stays 9 and held against tipping relatively to said stays by means of tension members 10 united to the inner end of said jib and to the lower ends of said stays. Mounted at the lower ends of the stays 9 is a roller foot 11 in which are journaled frusto-conical caster wheels 12 adapted to the annular step 6, thereby imposing the vertical load of the crane upon said step and adapting it to traverse the step in the arcuate movements of the crane. Mounted upon the inner end of the jib 8 is a strap 13 surrounding the post 1 and carrying anti-friction rollers 14 through which it bears upon the post. The ends of strap 13 extend parallel with and overlap the inner end of the jib, and in

order to sustain the jib horizontally are provided with rods 15 having eyes 16 receiving bolts 17 in the ends of the straps, and passing, at their outer ends, through a yoke 18 mounted upon the jib preferably over the upper ends of the stays 9, where the rods are adjustably secured by nuts 19.

The jib 8 is preferably constructed of a pair of channel members 8^a having their channels presented in opposite directions in order to provide a track for a trolley, and these channels are united at top by means of a plate 20 secured thereto by rivets 21. The stays 9 are riveted to the respective members 8^a with intervening reinforce plates 22. The inner ends of the jib members 8^a are united by an outer channel piece 23 and an inner angle piece 24. Vertical tension members 10 are secured to the jib members 8^a through the medium of said channel piece and angle piece, and the connection is reinforced by an angle piece 25.

Strap 13, while held firmly against vertical and transverse displacement relatively to the jib 8, is movable longitudinally thereon in order to permit of take up through the rods 15 and nuts 19; and to this end, the strap is secured to the jib by means of clips 26 and by a plate 27, which latter is connected by bolts 28 with the channel piece 23 and angle piece 24 without passing through the strap. The spaced channel members 8 of the jib yoked together at their inner ends by the transverse channel piece 23 and at their intermediate portions by means of the transverse yoke 18, and the similar dual construction of the stays, consisting of the diagonal compression members 9 spaced apart at their upper ends by attachment to the jib members 8 beneath the yoke 18 and at their lower ends by means of the roller foot 11, which constitutes a load transmitting yoke for the stays and which carries the spaced conical rollers 12 presented radially to the conical step 6, cooperate to provide a very stable but light and cheaply fabricated structure.

In order to mount the water, steam, air, or other pipe upon the post 1, said post is provided with a tubular conduit 29 extending from a point above the strap 13 to a point below the collar 5, and having its ends welded in the wall of the post so that a pipe, such as that illustrated at 30, can be readily driven through the conduit without interfering with the horizontal swinging of the crane and have its ends suitably connected to a supply main 31 and delivery connection 32.

According to Figure 4, the post is composed of a core or body 33 which extends the full length of the post, and a reinforcing jacket or lagging 34 constructed of surrounding timbers secured upon the body portion through hoops or bands 35, 36, said

reinforcing portion being turned or dressed at an intermediate point in order to provide an annular beveled step 6^a.

The crane in Figure 4 is constructed substantially as in Figure 1, and the description and reference characters of Figure 1 will apply thereto, except that its lower end or foot instead of being equipped with caster rollers secured to the stays by shoes, has a wooden block 37 secured between the stays 9 and constructed with a bearing end 37^a conforming to the step 6^a which sustains the vertical load of the crane while permitting its freedom of horizontal swinging. In both Figures 1 and 4, an additional strap 38 is preferably employed to resist displacement of the lower end of the crane, and this strap is preferably attached to tension members 10.

Preferably, the flange coupling between the post and the timber 4 is braced by struts 39 inserted between it and inset blocks 40, and also by guy rods 41.

I claim:

1. In a crane, a jib, a strap at the inner end of said jib, adapted to surround a post, and having its ends extending outwardly in the direction of the length of the jib and confined against transverse movement relative to the jib, but movable in said direction, and tie rods connected with the ends of said strap and adjustably anchored on the crane.

2. In a crane, a jib, a substantially U-shaped strap at the inner end of the jib adapted to surround a post and having ends extending in the longitudinal direction of and overlapping said jib, means securing the ends of the strap to the jib with movement in said longitudinal direction, tie rods connected with said strap ends, an anchorage for said tie rods on the crane, and means for adjusting the tie rods in their said anchorage.

3. In a crane, a jib comprising a pair of substantially horizontal spaced members, a transverse yoke uniting said members, stays extending from said yoke downwardly and inwardly to a point beneath the inner end of the jib, a strap mounted on the inner end of the jib adapted to connect it revolubly with the post, means adjustably connecting the strap with said yoke, tension members connecting the inner ends of the jib members with the lower ends of the stays, and means carried by the lower ends of the stays for vertically supporting the crane.

4. In a crane, a jib, comprising a pair of substantially horizontal spaced members, a strap, adapted to engage a crane-supporting post, having its ends extending in substantial parallelism with said spaced jib members and secured to the jib, a yoke secured transversely to said jib members at a point remote from the strap, said yoke spacing said jib members apart, a pair of stay members having their upper ends secured to said

jib members adjacent to said yoke and spaced apart thereby and extending downwardly and inwardly therefrom, a roller foot secured to and spacing apart the lower ends of said stay members and providing a load transmitting yoke therefor, and bearing rollers mounted on said load trans-

mitting yoke in substantial continuation of the respective stay members and spaced apart thereby in positions to rest upon a vertical support.

Signed at Chicago, Illinois, this 26th day of Sept., 1922.

SPENCER OTIS.
